UNITED STATES PATENT OFFICE.

GILBERT HENRY DAVIDSON, OF MORENCI, ARIZONA TERRITORY.

ELEVATOR.

No. 893,456.

Specification of Letters Patent.

Patented July 14, 1908.

Application filed November 5, 1907. Serial No. 400,797.

To all whom it may concern:

Be it known that I, GILBERT HENRY DAVIDSON, a citizen of the United States, and a resident of Morenci, in the county of Graham and 5 Territory of Arizona, have invented a new and Improved Elevator, of which the following is a full, clear, and exact description.

This invention relates to improvements in elevators, and is particularly useful in washing, separating and raising ore concentrates 10 and the like.

An object of the invention is to provide a simple, strong and efficient elevator for raising ore concentrates and the like from washing tanks or separators, and discharging the same at a point remote from the container.

A further object of the invention is to provide a device of the class described, having carriers for raising material from a tank or 20 container, and means for guiding the carriers so that they are inverted and discharged at a point in line with the direction of travel of the carrier.

A still further object of the invention is to 25 provide a device of the class described, serving to elevate the material from a tank or container, and having means for advancing the material of greater specific gravity toward the elevator carriers and permitting 30 the material of lower specific gravity to escape from the container.

The invention consists in the construction and combination of parts to be more fully described hereinafter and particularly set 35 forth in the claims.

Reference is to be had to the accompanying drawings forming a part of this specification, in which similar characters of reference indicate corresponding parts in all the 40 views, and in which

Figure 1 is a longitudinal section of the elevator on the line 1—1 of Fig. 2; Fig. 2 is a transverse section on the line 2—2 of Fig. 1; Fig. 3 is an end elevation of the device showing 45 a part broken away; and Fig. 4 is an enlarged longitudinal section of a detail.

Before proceeding to a more detailed explanation of my invention, it should be clearly understood that the same is designed 50 particularly for elevating or raising granular material such as ore concentrates and the like, from tanks, containers or separators. However, the underlying principle of the

carrier arrangement of the elevator can be used in connection with elevators designed 55 for other purposes, for instance, those used in simply advancing material from one point to another. My invention when used in ore concentration and similar operations facilitates the separation of the material of greater 60 and of less specific gravity, as will appear more clearly hereinafter. The device is also particularly useful in connection with tanks for washing granular material and for removing the material from the liquid within 65 said tanks. I prefer to employ a special form of tank or container as is shown in the drawings, though the construction of the same can be varied if so desired, to suit individual 70 preference or special conditions.

Referring more particularly to the drawings, I provide a tank or container 1 which may be fashioned from any suitable material and has the side 2 near the inlet end inclined. If so desired, a chute or inclined guideway 3 75 can be used for directing the material into the container. At the opposite side, the container has an overflow 4 permitting the escape of the liquid 5 within the container.

An inclined frame 6 having sides 7 and cross-members 8, has the lower end arranged in the container 1 adjacent to the inlet end of the same, as is shown most clearly in Fig. 1. The sides 7 of the frame carry bearing brackets 9, 10 and 11. The corresponding pairs of brackets are alined and have shafts 12, 13 and 14, respectively, journaled therein. The arrangement is such that the shafts 12 and 14 are near the upper and lower ends respectively, of the frames, while the shaft 13 is arranged between the end shafts. The respective shafts carry drums 15, 16 and 17.

An endless flexible band 18, fashioned from suitable belt material is arranged upon the drums 12, 13 and 14, and has the opposite runs 18^a and 18^b crossed between the drums 12 and 13. Adjacent to the crossing of the belt runs the frame 6 has a transverse member 19, and at the opposite side supports 20, carrying a similar transverse member 21. A shaft 22 is mounted upon the members 19 and 21 and extends between the belt runs, having a roller 23 tapered toward the ends and serving to separate the belt runs 100 and prevent their engagement. The band 18 has carriers 24, presenting laterally dis-

posed flanges 25, secured by rivets or screws 26 to the band. It will be understood that the carriers may be of any suitable form and may be mounted upon the band in any preferred or common manner. The carriers are preferably arranged so that they are substantially parallel to the horizontal plane when traveling in the normal direction of the band or belt runs.

10 I provide a discharge hopper 27, adjacent to the drum 15 and arranged to receive the material elevated by the carriers. The arrangement is such that the run 18^a of the belt has upwardly moving carriers. The 15 crossing of the belt runs causes the carriers to deviate from the normal direction of movement, and to be inverted in passing over the drum 15 before they reach a point permitting them to discharge the material carried, into the discharge hopper 27. This arrangement permits the placing of the discharge hopper in a most advantageous location. Ordinarily, when the carrier belt runs are not crossed, the discharge hopper must 20 necessarily be placed at the upper side of the inclined band. Owing to the inclined position of the frame carrying the traveling belt, it is difficult to place the discharge hopper close to the run of the belt without interfering 25 with the operation of the same. My arrangement, however, permits the discharge hopper to be located directly under the inverted and discharging carriers as is shown most clearly in Fig. 1.

30 A shaft 28, journaled in suitable bearings 29, located at opposite sides of the container 1, has a reel 30. The shaft 28 has a pulley 31, connected by means of a belt 32 with a driving pulley 33. The latter is mounted upon a 35 shaft 34, journaled upon bearing supports 35 secured to the sides of the container 1 and the sides 7 of the frame 6. The shaft 34 has a driving drum 36 engaging the under side of the belt run 18^b and driven thereby, and in 40 turn actuating the reel 30 through the belt 32 and the pulleys 31 and 33. As the reel arms rotate they pass into the container and advance the material toward the carriers. The heavier material, which settles near the 45 bottom of the container, is pushed by the reel arms toward the carriers, while the lighter material nearer the top of the container is not acted upon by the reel and passes with the liquid over the overflow 4 and thus escapes from the container. The 50 material is introduced into the container at the inlet end 2 and slides down the inclined side to a position where the major part of it is seized by the carriers and elevated to the 55 discharge hopper 27. The moisture in the material on the carriers drains off as the latter advances toward the discharge hopper and thus the material reaches the latter with 60 little adhering moisture.

Having thus described my invention, I claim as new, and desire to secure by Letters Patent:—

1. In a device of the class described, a traveling carrier for elevating material from a container, and means for guiding said carrier whereby the same is inverted to discharge at a point in line with the direction of its travel.

2. In a device of the class described, carriers mounted to travel, and serving successively to elevate the material from a container, and means for guiding said carriers whereby said carriers deviate from the normal direction of their travel and are inverted to discharge at the same side as the normal direction of their travel.

3. A device of the class described, comprising a container, carriers mounted to travel and to elevate material from said container, and means for guiding said carriers, whereby said carriers deviate from the normal direction of travel and are inverted, said carriers being further guided to discharge at a point in line with the normal direction of their travel.

4. A device of the class described, comprising a container, traveling carriers for elevating material from said container, means for guiding said carriers, whereby the same discharge at a point in line with the direction of their travel, and means for advancing material in said container toward said carriers.

5. A device of the class described, comprising a container, and an endless flexible band having carriers and arranged to elevate material from said container, said band having the runs crossed, whereby said carriers deviate from a normal direction of travel and discharge at a point in line with the normal direction.

6. A device of the class described, comprising a container, a frame-work having drums, and endless flexible band arranged to travel over said drums and having carriers serving to elevate material from said container, said band having the runs crossed, and means for advancing material in said container toward said band.

7. A device of the class described, comprising a container, a frame having one end in said container and carrying drums, one of said drums being located within said container, an endless flexible band passing over said drums and having carriers serving to elevate material from said container, said band having the runs crossed intermediate of said drums, and means for advancing material within said container toward said drum within said container.

8. A device of the class described, comprising a container, a frame having one end arranged within said container and having

drums, one of said drums being arranged within said container, an endless flexible band arranged to travel over said drums and having the runs crossed intermediate of said 5 drums, a further drum intermediate of said first drums, said runs being crossed between said first drum remote from said container and said further drum, a roller carried by said frame and separating the runs of said 10 band at the crossing of the same, a reel for advancing material within said container toward said first drum within said container, and means for driving said reel through the movement of said band.

15 9. A device of the class described, comprising a container having an inclined side and opposite thereto an overflow outlet, a frame having one end arranged within said container adjacent to said inclined side and 20 carrying drums, one of said drums being adjacent to said inclined side, an endless flexible band mounted upon said drums and having the runs crossed, said band being provided with carriers, and means operated by 25 said band for advancing material toward said inclined side of said container.

10. In a device of the class described, a frame having drums, an endless flexible band arranged to travel over said drums, said band 30 being provided with carriers and having the

runs crossed, whereby said carriers deviate from a normal direction of travel and discharge at a point in line with the normal direction of travel.

11. In a device of the class described, a 35 frame having drums, an endless flexible band arranged to travel over said drums and having carriers, the runs of said band being crossed intermediate of said drums, and a roller arranged between the runs of said band 40 at their point of crossing.

12. In a device of the class described, a frame having drums near the ends thereof, and a further drum intermediate of said first drums, an endless flexible band arranged to 45 travel over said drums and having carriers, the runs of said band being crossed intermediate of said further drum and one of said first drums, and a roller arranged between the runs of said band at the point of the 50 crossing of the runs.

In testimony whereof I have signed my name to this specification in the presence of subscribing witnesses.
